UNITED STATES PATENT OFFICE.

DOROTHY HIRSHFELD, OF LOS ANGELES, CALIFORNIA.

DESIGN FOR A CORSET.

52,915.

Specification for Design.

Patented Jan. 28, 1919.

Application filed June 14, 1918. Serial No. 240,083. Term of patent 14 years.

To all whom it may concern:

Be it known that I, DOROTHY HIRSHFELD, a citizen of the United States, residing at Los Angeles, in the county of Los Angeles and State of California, have invented a new, original, and ornamental Design for Corsets, of which the following is a specification, reference being had to the accompanying drawing, forming a part thereof.

Fig. 2 is a rear view; and
Fig. 3 is a side view.

I claim:

The ornamental design for a corset, as shown.

DOROTHY HIRSHFELD.

Witnesses:

ELSIE J. KERN,
JOHN M. NUTT.
